ABSTRACT OF THE DISCLOSURE

This invention deals with an automatic quilting machine having a plurality of needles for making a bonded quilted fabric comprised of a face fabric, a central padding and an underlying elastic fabric stretchable in warp direction. A transversely movable carriage supports the rolls driving the three materials in the warp or longitudinal direction. A programming device, actuating an electromagnetic coupling or an electromagnetic brake, allows either the transverse or the longitudinal movement or both of them, simultaneously, conveniently combined, in order to obtain any desired quilting design on the bonded fabric, the machine also being provided with a further device for keeping the underlying elastic fabric under adjustable tension in the warp direction.

My present invention relates to an automatic quilting machine, in which I provide a quilting programming device, which through an electric control synchronizes a system of electromagnetic brakes and couplings for composing any desired quilting pattern or design, according to the fancy and taste of the operator, designer or customer as the case may be, as well as a fabric quilting tension adjusting device, as will be more fully disclosed hereinafter.

The automatic quilting machine according to my present invention allows production of a bonded and quilted fabric which is comprised of a conventional non-expansion fabric bonded to a warp stretch fabric, that is a fabric being stretchable in the chain or warp direction, said warp stretch fabric being kept under tension in such a direction and quilted according to the programmed patterns, so that when tension is released I obtain a bonded and quilted fabric with any desired quilting design and with high stretch properties, making it particularly suitable for the production of sports wear, all other quilted apparel, bedding, and textile home furnishings in general.

Between the non-expansion plain fabric, which is the face cloth, and the warp stretch fabric, used as an underlying backing, a padding layer is inserted and quilted together with said fabrics. This padding layer may consist of wadding, foamed plastics and/or other suitable materials, so as to give to the fabric, besides a high insulating degree, also a particularly soft hand.

These and other objects of my invention, as well as its features and advantages, will be readily understood from the following detailed description of a preferred embodiment of the automatic stretch quilting machine of the invention, reference being made to the accompanying drawings, in which:

FIG. 1 is a diagrammatic perspective view of the quilting machine, and

FIG. 2 is an exploded perspective view, with parts omitted, of the main elements of the novel devices for the quilting machine according to my invention.

Referring now to the accompanying drawings, it will be understood that the entire quilting machine will not be described in detail, since its construction and operation are well known. I will illustrate and describe only

those parts forming the novel devices of the invention or being related and/or co-operating therewith.

From the main drive shaft A, driven by a suitable motor N through a suitable drive belt O, two motions are derived, namely a transverse motion of carriage B for transverse stitching and a longitudinal motion of rolls C₁ and C₂ for longitudinal stitching. These two motions, respectively obtained from carriage B and rolls C₁ and C₂, move the fabrics in relation to a plurality of needles Z, which are of the conventional types usually provided on quilting machines, so as to obtain different paths of stitches, forming the desired design.

The transverse stitching motion is obtained through a transmission comprised of a worm D₁ and a worm wheel D₂ having a shaft T on which an interchangeable cam E and a programming disc F are mounted.

Cam E, through two rollers or cam followers G₁ and G₂ and a plate, controls transverse movement W₁ of the fabric holding carriage B.

Programming disc F has a peripheral row of holes L in which suitable pins I may be threaded; said pins I protrude upwards from disc F and when rotating actuate a microswitch M, which through suitable not shown circuitry effects switching of electromagnetic coupling X and electromagnetic brake Y.

The composition of the various quilting patterns is therefore based on two directions at right angles to one another, that is to say rotation and the lengthwise pull W₂ of rolls C₁ and C₂ and transverse movement W₁ of carriage B.

If the two motions W₁ and W₂ are caused to occur at the same time, I obtain diagonal stitches. With suitable variations in the arrangement of pins I and by replacing cam E with other cams having a suitable contour, I obtain a great number of quilting patterns. Moreover, the transverse stitching and the vertical, lengthwise, stitching may be obtained independently from one another.

As already stated, electromagnetic coupling X has the object of engaging or disengaging the rolls C₁ and C₂ causing the advancement or pull W₂ on the fabric or, alternatively, the stopping of the rotation of such rolls and the longitudinal movement of the fabric. When electromagnetic coupling X is disengaged, my quilting machine will carry out only transverse stitching obtained through movement W₁ of carriage B by means of the cam E. In this case electromagnetic brake Y is energized for stopping motion of roll R₁ of the upper fabric so as to obtain only a horizontal stitching.

On the contrary, when electromagnetic coupling X is energized and cam E has a portion of its contour concentric with shaft T, said cam E will not actuate, for the period of time corresponding to the rotation of such a concentric portion of its contour, transverse movement W₁ of carriage B, thus obtaining only a longitudinal stitching due to the lengthwise pull W₂ caused by winding of the rolls C₁ and C₂. In this latter case carriage B is stationary because of the concentric portion of the cam E contour while fabric is being advanced through transmission S taken from main shaft A.

This possibility of carrying out transverse stitching and vertical, longitudinal, stitching independently from one another is one of the main features of my present invention and the sequence may be varied at will according to the sequence of actuations of microswitch M.

However, another main feature of my invention is just the contrary possibility, i.e. that of causing both transverse movement W₁ of carriage B due to the cam E, and pull W₂ due to the rotation of rolls C₁ and C₂ (viz. fabric advancement), to operate at the same time for any desired period of time, so as to obtain a diagonal stitching. This diagonal stitching can be more or less sloping,

straight, or curved with variable radius, or any combination thereof, simply by varying the contour of cam E and by advancing the speed of the fabric.

The automatic quilting machine according to my invention is therefore adapted to carry out any kind of quilting work by means of these improvements and may be regarded as a universal machine.

Automatic switching sequence between electromagnetic coupling X and electromagnetic brake Y through microswitch M is obtained by electrical equipment Q which is also used as a control board. In this equipment I provide all the elements for sequence generation, switching, conversion of electric power from alternate current into direct current for feeding said coupling X and brake Y; however, since all these elements are well known in the art and may be of any conventional type, no specific disclosure is deemed to be necessary.

As already stated, the warp stretch fabric has to be maintained under such a tension during quilting operation and for this purpose I provide the tension adjusting device which will now be described.

Said tension adjusting device is comprised of two supports 1 and 2 bearing roll R₃ for the warp stretch fabric, which is being delivered under needles Z in a lower position in respect to plain fabric starting from roll R₁ and padding which is unwound from the middle roll R₂. This device further comprises two rolls 3 and 4 causing the warp stretch fabric to be stretched for its whole width so as to keep it under tension. Said tension is obtained through an electromagnetic brake 5, acting on the shaft of the roll 3, said brake 5 being energized at tension percentages, which may be adjusted through a rheostat P, located in the control board Q, suitably scaled and calibrated in percentages of tension or stretch.

Said tension adjusting device allows, through rheostat P and electromagnetic brake 5, a variable control of tension of the warp stretch fabric, and this makes it possible to obtain a bonded quilted fabric with any desired degree of stretch.

It is to be understood that many modifications, variations, and additions may be applied to the various constructive parts of the quilting machine according to my present invention, without departing from the spirit thereof.

Having thus described my invention, what I claim as new and desire to secure by Letters Patent of the United States is:

1. An automatic quilting machine for making a bonded quilted fabric consisting of a face layer, a central padding layer and an underlying warp stretch layer, comprising:

a plurality of stitching needles for bonding said layers; three rolls each supporting one of said three layers to be bonded, and means to longitudinally move said layers with respect to said plurality of needles; a carriage supporting said three rolls and being transversely movable with respect to said plurality of needles, and means to transversely move said car-

riage with respect to said needles and independent of said longitudinal movement; means to control said independent transverse motion of said carriage and said independent longitudinal motion of said layers; and means upstream from said needles for keeping said warp stretch layer under tension in the warp direction.

2. An automatic quilting machine in accordance with claim 1, wherein said means to move said layers comprises a motor and a main driving shaft driven by said motor; and wherein said means to control said independent transverse and longitudinal motions comprises a second shaft driven by said main shaft and an interchangeable cam carried by said second shaft, said cam being adapted to transversely move said carriage.

3. The automatic quilting machine according to claim 2 wherein said means to control transverse and longitudinal motions further comprises an electromagnetic coupling which engages or disengages said means for longitudinally feeding said three layers.

4. The automatic quilting machine according to claim 2, wherein said roll supporting the face layer is provided with an electromagnetic brake.

5. The automatic quilting machine according to claim 1, wherein the programming device comprises an interchangeable programming disc having on its periphery a plurality of protruding pins actuating a microswitch for operating said electromagnetic coupling and said electromagnetic brake.

6. The automatic quilting machine according to claim 1, wherein the means for keeping under tension said warp stretch layer is adjustable and is comprised of two tension rollers, one said roller being provided with an electromagnetic brake which is provided with variable tension by means of a rheostat.
